(57) **CLAIM**

The ornamental design for a toy dog, as shown and described.

DESCRIPTION

FIG. 1 is a top perspective view of a toy dog showing my new design;

FIG. 2 is a rear perspective view thereof;

FIG. 3 is a bottom perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The broken line showing of the toy dog is for the purpose of illustrating portions of the article that forms no part of the claimed design.
